UNITED STATES PATENT OFFICE.

RICHARD W. GRIMES AND JOHN FERN, OF SCRANTON, PENNSYLVANIA.

MINER'S LAMP.

SPECIFICATION forming part of Letters Patent No. 280,738, dated July 3, 1883.

Application filed March 31, 1883. (No model.)

To all whom it may concern:

Be it known that we, RICHARD W. GRIMES and JOHN FERN, of Scranton, in the county of Lackawanna and State of Pennsylvania, have 5 invented certain new and useful Improvements in Miner's Lamps; and we do hereby declare the following to be a full, clear, and exact description of the invention, such as will enable others skilled in the art to which it appertains 10 to make and use the same.

Our invention relates to an improvement in miner's lamps.

Heretofore it has been a great source of annoyance and expense to miners to raise the 15 wicks of their lamps, which they do in various ways, preferably by a sharp pin, in the absence of which they strike the lamp on their shoe, a stone, or any convenient article. Both 20 of these methods are objectionable, the former because the necessary pin is often missing, and also because with this instrument a large portion of the wick is wasted, in that the wick cannot be raised evenly. The latter method is 25 objectionable, in that it necessitates the loss of a large quantity of oil by jarring the top open, and also because in a short time the lamp is destroyed from the constant knocking it receives.

The object of our invention is to overcome 30 this objectionable feature by providing an attachment which shall be adapted to raise the wick to any desired height, which may be applied to any ordinary construction of miner's lamp, and which shall be simple in construction and of few parts; and with this object in 35 view our invention consists in certain details of construction and combinations of parts, as will be hereinafter fully set forth, and pointed out in the claims.

40 In the accompanying drawings, Figures 1 and 4 are views of an ordinary miner's lamp in side elevation with our improvement attached thereto. Fig. 2 is a view of the same, showing our improvement detached therefrom. 45 Fig. 3 is a view of the same, showing the slide removed.

A represents the body of the lamp, and B the spout. Around the spout B fits a sleeve, C, provided on one side, at the lower end, with 50 a flange, a. The spout B is provided near its lower end with a catch, b, adapted to engage

with the flange a, and thus hold the sleeve C in position on the spout. The sleeve C is also provided near its upper end with two parallel tubular guides, c c, of equal length, and running longitudinally the length of the sleeve. 55 Near the lower end of this spout B, and in direct lines with the guides c c, are the guides c' c'. Through these guides c c' run the arms D, which are bent at their upper ends in the 60 form of a semicircle.

Between the guides c and c', and secured to or made integral with the arms D, are the lugs or stops d. Thus it will be seen that the longitudinal movement of the arms D is limited 65 by the lugs d striking the guides c or c'. It will also be observed that by turning the arms D so that the lugs d will approach each other the curved ends of the arms D will move from each other, and that by pushing the lugs apart 70 or away from each other the curved ends approach or pass each other. E represents a slide provided with two oblique slots or guides, e. This slide is placed over the arms D and guides c c', the lugs d projecting through the 75 oblique slots e. A bolt or rivet, h, passing through the slide E and traveling between the guides c c', is adapted to keep the slide E in position.

Having described the construction of our 80 improvement, we will now set forth its operation.

We will suppose, for the purpose of illustration, that the parts are in the position shown in Fig. 1, the lamp being lit, and that 85 it is necessary to raise the wick G. All that is necessary is to simply push the slide E toward the upper end of the sleeve, this movement, through means of the oblique slots formed in the slide E, separating or pushing 90 away from each other the lugs d, thereby bringing the curved ends of the arms D together, and thus grasping tightly the wick G. These lugs continue to separate until they strike the lower end of the oblique slots e, where they 95 are carried upward by the slide E. As the curved ends of the arms D have tightly grasped the wick G, the upward movement given to these arms also carries the wick in the same direction. As already described, the 100 upward movement is limited by the lugs d striking the guides c. After the wick has

been raised the necessary distance, the slide is pressed downward, this movement bringing the lugs *d* together until they strike the end of the slots, thus opening the curved end of the arms *D*. When the lugs strike the upper end of the oblique slots they are brought down with the slide *E*, thus placing the curved ends of the arms in position to take hold of the wick again. By simply raising the catch *b* the sleeve 10 may be slipped off of the spout *B*, thus leaving the ordinary lamp.

If desired, our improved device may be somewhat reduced in weight by making the sleeve in skeleton form, having sufficient surface for the attachment of the several necessary parts.

Our invention is equally well adapted for torches or other lamps or lanterns using a wick similar to the one herein shown. It is exceedingly simple in construction, is of few parts, may be applied to any ordinary miner's lamp, may be operated while the lamp is lit, and can be manufactured at a small initial cost.

We would have it understood that we do not limit ourselves to the precise construction herein shown and described, but consider ourselves at liberty to make such changes and alterations as fairly fall within the spirit and scope of our invention.

Having fully described our invention, what we claim as new, and desire to secure by Letters Patent, is—

1. The combination, with a lamp having a wick-tube, of devices secured to the tube and adapted to engage the wick above the tube for the purpose of elevating said wick.

2. The combination, with a lamp having a wick-tube, of movable arms, the upper curved ends of which embrace or partly embrace the wick beyond said tube for the purpose of raising said wick.

3. The combination, with a lamp provided with a wick tube or spout, of a movable sleeve adapted to fit on said wick tube or spout, and devices secured to the said sleeve, and extending beyond the tube, whereby the wick may be raised.

4. The combination, with a lamp provided with a wick tube or spout, of a sleeve removably secured to said wick tube or spout, arms the upper curved ends of which embrace the wick above the spout, and a device for closing the upper curved ends of the arms on the wick and moving the arms and wick outward.

5. The combination of a lamp and a sleeve

removably secured to the spout thereof, said sleeve being provided with a slide and means connected therewith whereby the wick of the lamp may be raised.

6. The combination, with a lamp and a sleeve 60 removably secured to the spout thereof, said sleeve being provided with guides, of arms adapted to move in said guides, and mechanism whereby said arms are operated to lift the wick of said lamp.

7. The combination of a lamp and a sleeve 65 removably secured to the spout thereof, said sleeve being provided with guides, arms adapted to move in said guides, and having their upper ends bent in the form of a semicircle, 70 and a slide adapted to operate said arms, whereby the latter will close around the wick of said lamp and carry it upward.

8. The combination of a lamp and a sleeve 75 removably secured to the spout thereof, said sleeve being provided with guides, arms adapted to move in the guides, and having their upper ends bent in the form of a semicircle, 80 said arms being also provided with lugs, and a slide placed over said guides and arms, and adapted by means of the lugs formed on said arms to close the curved ends of the arms around the wick and carry it upward.

9. The combination of a lamp and a sleeve 85 removably secured to the spout thereof, said sleeve being provided with guides, arms moving in said guides, and having their upper ends bent in suitable form to grasp the wick of said lamp, a slide placed over said guides, and provided with two oblique slots or guides 90 adapted to receive lugs formed on said arms, and a bolt or rivet passing through said slide, and moving between the guides formed on the sleeve, said bolt or rivet being adapted to hold the slide in position.

10. The combination, with the lamp *A* and sleeve *C*, adapted to be removably secured to the spout *B*, of the guides *c c'*, arms *D*, provided with curved ends and lugs or stops *d*, slide *E*, provided with oblique slots *e*, and bolt 100 or rivet *h*, all of the above parts combined and adapted to operate substantially as described.

In testimony whereof we have signed this specification in the presence of two subscribing witnesses.

RICHARD W. GRIMES.
JOHN FERN.
